(57) **CLAIM**

The ornamental design for medium low profile tilttable mount for flat panel display, substantially as shown and described.

DESCRIPTION

FIG. 1 is a top, left isometric view of a medium low profile tilttable mount for flat panel display; the top, right isometric view being a mirror image thereof.

FIG. 2 is a left side view thereof; the right side view being a mirror image thereof.

FIG. 3 is a top, elevational view thereof.

FIG. 4 is a rear, elevational view thereof.

FIG. 5 is a front, elevational view thereof; and,

FIG. 6 is a bottom, elevational view thereof.
